UNIT CONTAINER

William T. Hormes, Catonsville, Md.

Application August 20, 1942, Serial No. 455,481

3 Claims. (Cl. 312—146)

This invention is a cabinet unit container structure with inserts, standardized and interchangeable in character, and primarily intended for use in stores and mercantile establishments generally, although not limited to such use.

The construction is particularly designed to facilitate manufacture and marketing of the product, as well as varying merchant users' adaptation of it for rearrangement to space or change in merchandise accommodation.

In retail establishments, spaces in the lines of store equipment are used for display, as distinguished from the more general use of merchandise storing. Such spaces are usually free of shelves or units, are open at the front or enclosed by glass doors, and are usually electrically illuminated. The woodwork then being under illumination and in such instances forming a background for the merchandise being displayed, something better than the soft wood skeleton construction was necessary. Additional display units had to be installed for the purpose.

With the rapid and continuous rising of wage rates, and a declining cost of plywood, due to the marked advance in developments in plywood construction, it has been found worthwhile to change from the soft wood skeleton containers, relatively costly due to labor in machining and assembling, to a unit container of solid sheets of plywood with a face veneer of hardwood type, showing in the entire interior of the unit container. In this type of unit container there is no need to insert an additional unit for display purposes.

With the rather universal acceptance of the principle of streamlining in design, it has become general practice to depart considerably from the older straight line and right angle arrangement of store equipment and late store arrangements of space include considerable curving of the lines of containers. Such curving is now commonly accomplished by placing containers at an angle with respect to each other, while the cornice, by furring out where required, follows true curved lines.

Although cornices and pilasters have been detachably connected to the unit containers, angle setting thereof has required shaping of pilasters to conform to the angle. Change of space requirement, if accompanied by change of angle, required new, specially designed pilasters conforming to the changed angle.

Stores from time to time change the type of wood and finish of pilasters and cornice only, thus economically securing a pleasing appearance of newness to the store interior. With pilasters

and cornice both detachably connected, the change can be economically made without disturbing the body, or merchandise carrying equipment.

5 With these problems in view, one of the objects of the invention is to provide a unit container embodying plywood sheets, so constructed that the mere placing of a plurality of unit containers in juxtaposition will provide finished joints between the containers, eliminating the requirement of pilasters of conventional or special formation, irrespective of whether the unit containers are in alignment or are disposed at an angle with respect to each other.

10 A further object is to provide an ornamental molding strip in association with a unit container construction, having means for providing a line like continuous contact with a similar portion of an adjacently positioned molding strip, whereby 15 a pilaster-like appearance is provided at the joint between the containers, irrespective of whether they are in true alignment or are disposed at an angle with respect to each other, said molding strips being so positioned that a continuous cornice may be employed.

20 A further object is to provide a unit container possessing the above mentioned characteristics which is adapted for use with either the continuous type of cornice, or the unit type of cornice, as may be desired.

25 A further object is to have the ornamental molding strip, in addition to its function of forming a pilaster-like effect, to overlap the space between the edge of the inner face of the container and the ends of the units inserted in the container, thus locking said units within the container while the ornamental molding strip is in engagement with the end member of the container.

30 40 A further object is to provide means for detachably connecting the ornamental molding strip to permit ready removal of units from the container for rearrangement, or to substitute new strips of different wood or finish.

45 45 The invention will be hereinafter fully set forth and particularly pointed out in the claims.

In the accompanying drawings—

50 Figure 1 is a front elevation illustrating portions of a plurality of unit container structures constructed in accordance with the invention.

Figure 2 is a vertical sectional view on the line 2—2, somewhat enlarged.

55 Figure 3 is a detail sectional view on the line 3—3, Figure 2.

Figure 4 is a similar view of a slight modification.

Figure 5 is a detail sectional view illustrating the detachable connection between the end member and the molding strip.

Figures 6 and 7 are detail perspective views illustrating the engaging portions of the molding strip and the end member.

Figure 8 is a perspective view illustrative of a typical drawer unit to be placed in the cabinet.

Figure 9 is a perspective of a type of door-carrying frame to be inserted at the forward edge of the unit container, overlapped by the ornamental molding strip.

Referring to the drawings, C designates a unit container cabinet which may be of any desired construction, but for purposes of illustration is shown as an open front cabinet. Each unit container consists of two laterally spaced end walls or members 10, each of which carries a strip 11 secured in suitable manner to its inner face adjacent the top thereof. Only one of said strips is shown. Said strips 11 are joined to strips 12 carried by the rear wall 13 of the cabinet. The bottom 14 of the cabinet is secured to the lower portion of each end wall or member 10, and to the rear wall 13. Extending below the bottom 14 is a base member B provided with a front wall 15, and a rear wall 16. The top T rests upon the strips 11 and 12, as shown. The base is provided with a finishing molding 18.

The forward ends of the strips 11 are joined to a strip 19, commonly called a "blind cornice," which is disposed between and suitably secured to the end walls 10 at a position inside of the container at the front thereof. Slotted strips 20 are shown mounted in suitable recesses in the end walls, so as to receive removable shelf-supporting lugs for shelving S, in a manner well understood in the art.

The front edge of each of the end members 10 is provided with a longitudinal channel 21 which extends substantially throughout the vertical length of said end wall, or at least to a position adjacent the lower edge of the blind cornice 19. Molding strips M, one for each end wall 10, are provided to cover said channeled edges of the end walls. The rear edge or back of each molding strip M is provided with aligned, relatively spaced longitudinal tongue 22 complementary to the channel 21 of an end member 10, and each of said molding strips is of a width to extend beyond both side faces of each end member 10, so as to provide rear shoulders 23, 24, the shoulder 24 being somewhat wider than the shoulder 23.

The body portion of each molding strip M at the outer edge thereof, i. e., that edge which is contiguous to the shoulder 23, is provided with a longitudinal contact portion 25 so positioned as to have surface engagement with an identical contact portion of an adjacent molding strip M carried by an end member of an adjoining unit container. Said contact portion may be of any desired cross-sectional contour. For instance, said outer edge of the molding strip M may be provided with a rearward flat bevel 26 as shown in Figure 3, or it may be provided with an arcuate convex portion 28a, as shown in Figure 4. It is to be understood that these forms are shown solely for purposes of illustration and without intent to limit the invention thereto. In other words, the precise contour is immaterial as long as the outer edge of the molding strip has a rearwardly extended surface 27 along its said

outer edge, less than the thickness of the strip, which will meet a similar surface of an abutting molding strip in such manner as to provide a chamfer-like longitudinal recess 28.

5 Embedded within the front edge face of each end wall 10 is a lock plate 29 having a downwardly extending slot 30 which is positioned to be engaged by a headed stud or screw 31 located in the space between the tongue 22. In practice, the molding strip M is engaged with its end wall 10 by placing the tongue 22 in the channel 21, at a lowered position and then moving the strip upwardly until the stud 31 engages the slotted portion of the lock plate. In this way the rear face 15 of the molding is held in close contact with the front edge face of the end wall. The pressure of contact may be varied by adjustment of the screw 31. It will be observed that the engaging and disengaging movements of the molding are at an 20 angle to the path of movement of the insert. The lower portion of the molding strip is cut away as indicated at 32 to receive the molding 18, said cut-away portion being so proportioned that there will be a slight frictional engagement between 25 the shoulder formed thereby and the upper edge of the molding 18, which will be sufficient to normally maintain the molding strip in position.

In practice, when it is desired to place a plurality of unit containers in adjacent positions 30 they are arranged end for end, in straight line, or in any desired angular relationship, before the cornice 33 is placed in position. However, the unit container bodies must be slightly separated so as to insure that the contact-surfaces 25 of 35 the adjacent molding strips of each pair of adjacent unit containers are brought into engagement so that there is a full length contact of the engaged portions. In this way, the said adjacent engaged surfaces 25 of the molding strips 40 provide a finished appearance for the end walls 10 of the adjacent units, the meeting rearwardly extended surfaces 27 producing a chamfer-like effect simulating the appearance of a pilaster connecting the units, although each molding unit 45 is independently disconnectible from its end wall. It will be readily seen that if it becomes necessary or desirable to arrange the adjacent molding units at an angle with respect to each other instead of being in straight alignment, the contact of the portions 27 of the molding strips M 50 may be maintained throughout the extent of a considerable range of relative angular adjustment of the two units, as determined by the contour of the said surfaces 27.

55 If desired, cornices 33 may be provided in the usual and well known way, or a continuous cornice of the length desired may be removably secured in suitable manner to the blind cornices 19 of the respective unit containers of a group 60 extended along the upper portions of the unit containers which constitute said group. Various types of merchandise insert units i. e. units which are designed to support or contain merchandise may be removably supported within the unit 65 container C. As examples a drawer unit D is shown in Figure 8 and a door-supporting frame D' is shown in Figure 9. The frame D' comprises a rectangular frame mounted at the front portion of the unit container, and anchored therein 70 in suitable manner, as for instance by means of screws passed through openings d. When unit D' is employed to cover a space used for storage the doors d' are preferably constructed of wood, but if the space is to be used for display said doors 75 are preferably constructed of glass. It is to be

understood, however, that the invention is not limited to these particular designs of unit. Other types of such units are described and claimed in a copending application filed concurrently herewith. In practice, these units of whatever types that have been selected for use, must be inserted into the unit container while the molding strips M have been detached from the end members. In this connection each of said molding strips, in addition to its pilaster-like functions, performs the additional functions of retaining the merchandise carrying units within the container by means of shoulders 24. It will be observed that warping and twisting of the removable moldings is prevented by the tongue and groove engagement between the moldings and the end walls of the cabinet, thereby maintaining the margin of overlap of each shoulder 24. Each molding also overlaps the open front portion of the cabinet sufficiently to conceal the ends of the merchandise carrying units. To accomplish this result the length of each insert unit is slightly less than the space between the inner face of the end members 10 of the cabinet to which it is related.

After the desired units have been placed in position, the plate 29 of each molding strip M is engaged with a stud 31 carried by an end member, by an upward movement. The cornice serves as an abutment to limit such upward movement and the molding strip M then held in place by springing its lower end over and into frictional contact with molding 18.

The advantages of the invention will be readily understood by those skilled in the art to which it belongs. It will be particularly observed that a very simple and inexpensive arrangement is provided for finishing the spaces between a plurality of unit containers, which are situated closely adjacent to each other, whether they are in direct alignment, or are arranged at an angle with respect to each other. A further advantage is that the structure is so arranged that the ornamental line of juncture between adjacent containers may be provided irrespective of whether a continuous cornice is desired or not.

Another advantage of the invention lies in the fact that it is not uncommon in retail establishments to change the appearance from time to time of the layout and the physical equipment. It will be readily apparent that the layout may be easily changed by shifting the unit containers as well as rearranging the enclosing merchandise units for reception of different types of merchandise. This shifting may be readily accomplished with unit containers of the type herein described and claimed. In practice, both cornice and molding strips are usually of hardwood finish in a wide variation of shades, ranging from bleached to dark stained finishes and are detachably connected to the unit containers. With the detachably connected types of cornices and molding strips herein described, it is possible at a minimum of labor and expense, to advantageously vary the type of wood and finishes of the cornices and pilasters of any installation of container units, so as to vary the appearance of the installation thereof in a pleasing manner. It will be noted that the containers are correctly constructed and sized to always store and display the merchandise to best advantage, so that the architectural appearance may be readily and economically changed by substituting cornice and mold strip members of different contour and finish. It is obvious that the relative positions of

the channels 21 and ribs 22 may be reversed without departing from the spirit of the invention.

Having thus explained the nature of the invention and described an operative manner of constructing and using the same, although without attempting to set forth all of the forms in which it may be made, or all of the forms of its use, what is claimed is:

1. A store furniture construction for display of merchandise having in combination a container cabinet, a unit insert removably located within said container cabinet and having an overall width less than the spacing between the inner faces of the end walls of the container cabinet, whereby said unit insert may be removed from the container cabinet, a molding for each of the front edge faces of the said end walls, said molding being of a width to cover said end wall edge face and to also overlap the adjacent end of the inserted unit insert, the rear face of the molding and the end edge face of each end wall being provided with slidingly related tongue and groove engagement means, so as to maintain a predetermined uniform alignment of said overlap, the tongue being interrupted, a locking member extending transversely of the groove in the one face, a complementary locking member located in the space where said tongue is interrupted and provided with an engaging portion at a position to traverse said groove by relative longitudinal movement of the molding with respect to said end wall edge face to bring the said engaging portion into engagement with the rear of the said transversely disposed locking member, said complementary member being adjustable to vary the pressure of the engaging portion thereof with the rear of said transversely located member, said longitudinal movement being at an angle to the path of withdrawal of the tongue from the groove and the insert from the container cabinet, whereby interengagement of the complementary members will lock the tongue against removal from the groove and the unit insert from the container cabinet.
2. A store furniture construction for display of merchandise having in combination a container cabinet, a unit insert removably located within said container cabinet and having an overall width less than the spacing between the inner faces of the end walls of the container cabinet, whereby said unit insert may be removed from the container cabinet, a molding for each of the front edge faces of the said end walls, said molding being of a width to cover said end wall edge face and to also overlap the adjacent end of the inserted unit insert, the rear face of the molding having a longitudinally disposed tongue and the front edge face of each end wall having a groove complementary to and slidingly engageable with said tongue, so as to maintain a predetermined uniform alignment of said overlap, the tongue being interrupted, a slotted locking member secured to said front edge face of the end wall and extending transversely of the said groove, a locking stud located in the space where said tongue is interrupted and provided with a head at a position to traverse said groove by relative longitudinal movement of the molding with respect to said end wall edge face to bring said head into engagement with the rear of the slotted portion of said transversely disposed locking member, said stud being adjustable to vary the pressure of said head with the rear of said transversely positioned locking member, said longitudinal movement being at an angle to the path of

withdrawal of the tongue from the groove and the insert from the container cabinet, whereby interengagement of the complementary members will lock the tongue against removal from the groove and the unit insert from the container cabinet.

3. A store furniture construction for display of merchandise having in combination a container cabinet, a unit insert removably located within said container cabinet and having an overall width less than the spacing between the inner faces of the end walls of the container cabinet, whereby said unit insert may be removed from the container cabinet, a molding for each of the front edge faces of the said end walls, said molding being of a width to cover said end wall edge face and to also overlap the adjacent end of the inserted unit insert, the rear face of the molding and the end edge face of each end wall being provided with slidably related tongue and groove engagement means, so as to maintain a predetermined uniform alignment of said overlap, the tongue being interrupted, a locking member ex-

tending transversely of the groove in the one face, a complementary locking member located in the space where said tongue is interrupted and provided with an engaging portion at a position to traverse said groove by relative longitudinal movement of the molding with respect to said end wall edge face to bring the said engaging portion into engagement with the rear of the said transversely disposed locking member, said longitudinal movement being at an angle to the path of withdrawal of the tongue from the groove and the insert from the container cabinet, whereby interengagement of the complementary members will lock the tongue against removal from the groove and the unit insert from the container cabinet, and a fixed anchor strip carried by a portion of the container cabinet, said strip being at an angle to the path of disengaging movement of the tongue from the groove, whereby interlocking engagement of the adjacent end of the molding with the anchor strip will lock said molding against disengagement.

WILLIAM T. HORMES.
